UNITED STATES PATENT OFFICE.

THOMAS POUCHER, OF ST. LOUIS, MISSOURI.

BOOK AND PROCESS OF MAKING SAME.

Application filed February 9, 1921. Serial No. 443,668.

To all whom it may concern:

Be it known that I, THOMAS POUCHER, a citizen of the United States, and a resident of the city of St. Louis and State of Missouri, have invented a new and useful Improvement in Book and Process of Making Same, of which the following is a specification.

My invention relates to books and more particularly to the covers of small books, such as note, memorandum and bank books, and to the manner of securing the book-leaves and covers together. In the manufacture of such books, the practice has been to make the cover of two side pieces of heavy cardboard, which are placed alongside of each other with their adjacent side margins spaced apart, and then cover said side pieces with a material whose marginal portions are folded over the marginal portions of the cardboard. The book-leaves are then sewed to a backing, which, in turn, is pasted to the inner faces of the side portions with its marginal portion lapping the folded-over marginal portions of the covering material. Such books are expensive to manufacture by reason of the number of operations required in assembling the various parts and also by reason of the number of parts and the different materials required. The folding of the marginal portions of the covering material over the marginal portions of the cardboard sides requires also that said covering shall be made larger than the size desired for the finished cover. Such books do not lie flat in either closed or opened position, as they should do for convenience in making entries therein and for stacking of said books when closed. The stiff cardboard sides of such books are unyielding in the user's pocket and are liable to become broken and result in an unsightly book.

The principal object of the present invention is to produce a book which will eliminate the disadvantages hereinbefore mentioned. Other objects are to reduce the number of parts which form the cover, to form the book cover of a piece of material of a size and shape desired for said cover, to reduce the number of operations, to simplify and improve the construction, and otherwise reduce the cost of manufacture. The invention consists principally in a book whose cover comprises a single piece of leather or similar material which has a band of reduced thickness; it also consists in notching the marginal portions of the trans-

parent strip which covers the window opening in the book-cover, and it also consists in the process of making said book and in the combination and arrangements of parts hereinafter described and claimed.

In the accompanying drawing, which forms part of this specification, and wherein like symbols refer to like parts wherever they occur,

Fig. 1 is a face view of a book embodying my invention, the cover being shown open;

Fig. 2 is an end view thereof;

Fig. 3 is a perspective view of the cover opened out flat;

Fig. 4 is an enlarged edge view of the cover in the region of the skived portion; and

Fig. 5 is an enlarged cross-section taken through the finished book in the region of the skived portion of the cover.

In the accompanying drawing my invention is shown in connection with a book of the kind used as a bank-book, but the invention is applicable to other types of books as well. In the book shown in the drawing, the cover 10 is made of a single piece of leather or like material which is cut out to the size and shape desired for the cover. The cover has a band of reduced thickness 80 across its middle portion, which extends from top to bottom of said cover and is preferably formed by skiving the inner surface of the leather. This skiving of a band in the middle portion of the cover 10 forms 85 a shallow groove or furrow 11 which extends from top to bottom thereof.

The sheets, which form the leaves 12, are of a shape corresponding to the shape of the cover 10, but are slightly smaller in size. 90 The sheets 12 are folded across the middle and brought together in book form to form the leaves 12 and are sewed as at 13 to the middle portion of a backing 14 of cloth or other suitable material of a size and shape corresponding to the size and shape of said leaves. The backing 14, with the leaves 12 secured thereto, is then pasted or otherwise secured to the inner surface of the cover 10.

Registering window openings 15 are then 105 cut in that portion of the cover which forms the front side of the finished cover and in that portion of the backing which is secured thereto. The side of the backing which has the opening formed therein is then pulled 110 away from the cover and the opening in said cover is then covered by a piece of celluloid

or other transparent material 16, whose notched or serrated marginal portion 17 are secured to the inner surface of the cover adjacent to the opening 15 therein by means of 5 the paste which secures the backing to the cover. The portion of the backing, which has been pulled away from the cover to permit the window to be placed in position, is then again pressed against the cover. This 10 action causes the portions of the backing located opposite to the notches in the region of the window to be pressed into said notches and adhere to the inner surface of the cover, thereby firmly holding said window in position.

15 The skiving of the middle portion of the cover 10 results in a flexible band or hinge portion whose width is greater than the combined thickness of the leaves 12. Thus, the 20 bending strain is not transferred to the sides of the cover, and the weight of the thicker side portions of the cover causes these portions to lie flat in both open and closed positions of the book.

25 Aside from the advantages above noted, books constructed in accordance with my invention can be furnished with leather covers considerably cheaper than old style books having covers of imitation leather. Also, 30 the edges of the hereinbefore described cover are less liable to wear and become torn than an old style book having stiff cloth-bound edges. Also, the cutting of the cover from a piece of material of the size and shape desired for the finished cover results in a 35 considerable saving of material and also eliminates the hereinbefore mentioned folding and pasting operation.

What I claim is:

40 1. The process of making books which consists in cutting a piece of leather or like material to the size and shape desired for the book-cover, reducing the thickness of said cover along the middle thereof to form a 45 hinge section, securing the book-leaves to a suitable backing along their line of folding, pasting the inner surface of said cover, mounting said backing on said pasted sur-

face with the folded portions of said book-leaves opposite to the thinned portion of 50 said cover, cutting a window opening through the front side of said cover and said backing, pulling said backing away from said cover adjacent to said window opening before the paste dries, covering the window opening 55 in said cover with a piece of transparent material having notched marginal portions which overlap the edges of said opening, and resetting the turned back portion of the backing on said cover.

2. The process of making books which consists in cutting a piece of leather or like material to the size and shape desired for the book-cover, reducing the thickness of said cover along the middle thereof to form a 60 hinge section, securing the book-leaves to a suitable backing along their line of folding, pasting the inner surface of said cover, mounting said backing on said pasted surface with the folded portions of said book-leaves opposite to the thinned portion of said cover, cutting a window opening through the front side of said cover and said backing, pulling said backing away from said cover adjacent to said window opening before the 65 paste dries, covering the window opening in said cover with a piece of transparent material and resetting the turned back portion of the backing on said cover.

3. The process of making books which consists in cutting a piece of leather or like material to the size and shape desired for the book-cover, securing the book-leaves to a suitable backing, pasting the inner surface of said cover, mounting said backing on said 70 pasted surface, cutting a window opening through said cover and said backing, pulling said backing away from said cover adjacent to said window opening before the paste 75 dries, covering the window opening in said cover with a piece of transparent material, and resetting the turned back portion of the backing on said cover.

Signed at St. Louis, Missouri, this 7th day of February, 1921.

THOMAS POUGHHER.
